UNITED STATES PATENT OFFICE.

JOHN KING RECKFORD, OF NEW YORK, N. Y.

DESIGN FOR A PENCIL TIP.

Application filed April 4, 1927. Serial No. 21,444. Term of patent 14 years.

To all whom it may concern:

Be it known that I, JOHN K. RECKFORD, a citizen of the United States, residing at New York, in the county and State of New York, have invented a new, original, and ornamental Design for Pencil Tips, of which the following is a specification, reference being had to the accompanying drawing, forming a part thereof.

The figure in the drawing is a perspective view of a pencil tip showing my new design.

I claim:

The ornamental design for a pencil tip, as shown.

In testimony whereof, I have signed my name to this specification this 2nd day of April, 1927.

JOHN KING RECKFORD.
